UNITED STATES PATENT OFFICE.

GUSTAV HORN, OF BRAUNSCHWEIG, GERMANY.

RETORT FOR THE MANUFACTURE OF GAS.

SPECIFICATION forming part of Letters Patent No. 783,435, dated February 28, 1905.

Application filed July 24, 1903. Serial No. 166,904.

To all whom it may concern:

Be it known that I, GUSTAV HORN, gas-engineer, a subject of the Emperor of Germany, residing at Braunschweig, in the Empire of Germany, (whose full postal address is 23 Nordstrasse, Braunschweig aforesaid,) have invented new and useful Improvements in Retorts for the Manufacture of Gas, (for which applications have been made in Germany, dated January 31, 1903, and in Great Britain, dated June 18, 1903,) of which the following is a specification.

This invention relates to retorts for the manufacture of gas which have channels at the top or at the bottom, or at both.

According to this invention the wall between the retort and a channel is formed of plates of refractory material arranged in steps in such a manner that a space is left between each two adjacent plates. For this purpose the plates may be provided with ribs or projections. The position of the plates is such that their faces are inclined toward the mouth through which the charge is drawn, and they project one over the other, so that no portion of the charge can obstruct the holes or spaces formed by the ribs. The plates may be fixed in the walls of the retort or may be laid loosely in recesses in the retort. It is especially advantageous to form the bottom of the upper channel of loosely-laid plates, for on account of the free movement of individual plates the top of the retort will possess a yielding power. Thus no damage is done to the retort by excess of pressure caused by the swelling of a fresh charge, which is usually so prejudicial.

The annexed drawings illustrate apparatus constructed according to this invention. Figure 1 is a vertical section of a furnace provided with the improved retort. Fig. 2 is a vertical section of the furnace according to the line *xx* of Fig. 1. Fig. 3 is a transverse section of the plates forming the wall between the channels and the charge-room of the retort. Fig. 4 is a longitudinal section of the plates according to the line *yy* of Fig. 3.

Three (but this number may be varied) retorts *a* are heated by the same furnace *p* and are each provided with two channels *b* and *c*, one at the top and the other at the bottom.

Both channels communicate with a gas-outlet pipe *d*. The top and the bottom of the retort, together with their channels, incline upward. The top *g* and the bottom *h* of the retort are composed of plates *l*, resting upon shoulders *i* or *k* on the inside of the retort. As shown in Figs. 3 and 4 they are provided with ribs *m* and *n*, so that while, on the one hand, they mutually support each other, on the other hand, free spaces are left between them through which the gas generated passes. The shape of the said plates may vary greatly; but it must be such that while resting as securely as possible and inclined toward the retort-mouth *o* the space between the plates allows the gas generated to pass freely away into the channels *b* and *c*, and the shape must also be such that the charge, ash, or the like cannot fall through the spaces into the bottom channel. The bottom channel may advantageously be used to pass vapor or the like through the layer of coke, and thus decompose the said vapor. For this purpose the vapor or the like is led into the lower end of the channel *c* through a suitable connecting-pipe *e*. At the top end of the channel *c* communication with the channel *b* is cut off by the damper *f*. Vapor or the like passing in through *e* is then compelled to divide up in its passage through the channel *c* and to pass equally throughout the layer of coke. In consequence of the vapor being thus divided up the mass of coke is not cooled to so great an extent, as usual, when the whole of the vapor or the like passes through the layer of coke at the same time.

I declare that what I claim is—

In a retort for the manufacture of gas, the combination with a furnace, retorts therein, channels in said retorts at the top and bottom thereof, walls formed of plates provided with ribs and arranged in steps between said channels and the interior of the retort, substantially as described.

In witness whereof I have hereunto set my hand in presence of two witnesses.

GUSTAV HORN.
